RAILWAY TRAFFIC CONTROLLING APPARATUS

Filed Dec. 3, 1929

UNITED STATES PATENT OFFICE

PAUL H. CRAGO, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed December 3, 1929. Serial No. 411,286.

My invention relates to railway traffic controlling apparatus, and particularly to apparatus for safely governing the movements of cars or trains at points where an electric railway intersects another railway.

I will describe one form of apparatus embodying my invention, and will then point out the novel features thereof in claims.

The accompanying drawing is a diagrammatic view illustrating one form of apparatus embodying my invention.

Referring to the drawing, the reference character A designates the track of an electric railway which intersects the track B of another railway at the point 1, and over each of which tracks traffic moves in both directions.

Associated with the track A is a current conductor, here shown as the usual trolley wire 2. The trolley wire 2 is connected with one terminal of a generator C, the other terminal of which is connected with the return conductor or ground at 3. It will be apparent, therefore, that the trolley wire 2 is constantly supplied with current which may be used both for propulsion and for the control of apparatus to be described in detail hereinafter.

The track B is provided with an insulated section a—b which extends in each direction from the point of intersection 1, and which is electrically insulated from points beyond and from the track A by insulated rail joints 4. Section a—b is provided with a track circuit comprising a suitable source of current, here shown as a battery 5, connected across the rails adjacent one end of the section, and a track relay D connected across the rails adjacent the other end of the section. It will be apparent, therefore, that in accordance with the usual practice, the track relay D will be energized when track B is unoccupied within the limits of the insulated section, and de-energized when a train occupies any part of the insulated section of this track.

The movement of cars approaching the point of intersection 1 over track A is governed by two derails E¹ and E², located in track A on opposite sides of the intersecting point 1, and arranged to cause derailment of

cars approaching the intersecting point. Each derail is controlled by suitable operating mechanism, designated by the reference character F with a distinguishing exponent corresponding to the exponent of the reference character for the associated derail. Referring to the operating mechanism F¹ for derail E¹, this mechanism, in the form here shown, comprises a plunger 6 operatively connected with the derail E¹ and controlled by two windings 7 and 8. When winding 7 is energized, the plunger 6 is moved upwardly and the derail E¹ is opened, as illustrated in the drawing. When winding 8 is energized however, the plunger 6 is moved downwardly and derail E¹ becomes closed. The operating mechanism F² for the derail E² is similar in form and operation to the operating mechanism F¹ for the derail E¹. Under normal conditions, the derails E¹ and E² are both open to cause derailment of any unauthorized train approaching the crossing from either direction on track A.

Associated with derail E¹ is a contact 9—9^a which is closed only when derail E¹ is closed, and associated with derail E² is a similar contact 10—10^a which is closed only when derail E² is closed.

The operating mechanisms F¹ and F² are controlled by the track relay D, and by two relays J¹ and J², each comprising a normal winding 11, a reverse winding 12, and a plurality of contact members movable into normal or reverse positions to close normal or reverse contacts according as the normal or reverse winding is energized. These relays are constructed in such manner that the contact members will remain in the positions to which they were last operated until positively moved out of these positions.

The relays J¹ and J², in turn, are controlled by four trolley contactors H¹, H², H³, and H⁴, each of which, in the form here shown, comprises a movable contact member 13, electrically connected with the trolley wire 2, and arranged to be moved momentarily into engagement with a fixed contact by the trolley of a car when the car passes the contactor. For example, an eastbound car, upon passing contactor H¹, will engage the contact mem-

ber 13 of this contactor and momentarily move it into engagement with a fixed contact 14 to close a contact 13-14. Similarly, an eastbound car, upon passing contactors H^2 , H^3 or H^4 will momentarily close the contact 13-14 of the corresponding contactor. Furthermore, a westbound car, upon passing contactors H^4 , H^3 , H^2 or H^1 , will momentarily close a contact 13-15 of the corresponding contactor.

10 The locations of contactors H^1 , H^2 , H^3 and H^4 will usually be such that an eastbound car will operate contactor H^1 just before it reaches derail E^1 , and will operate contactor H^2 just after it passes derail E^1 , while a westbound car will operate contactor H^4 just before it reaches derail E^2 and will operate contactor H^3 just after it passes derail E^2 .

The movement of northbound trains approaching the point of intersection 1 over section $a-b$ is controlled by a suitable roadside signal S^1 , and the movement of southbound trains approaching the point of intersection 1 over section $a-b$ is controlled by a similar signal S^2 . Each signal, as here shown, comprises two electric lamps G and R , adapted when illuminated, to indicate "proceed" and "stop", respectively.

30 The lamps G and R of each signal S may be controlled in any suitable manner. For example, as here shown, the green lamps G of the signals S¹ and S² are connected in multiple and are supplied with current from a battery L over a front contact 16-16^a of a 35 home relay K, and the red lamps R are likewise connected in multiple and are supplied with current from battery L over a back contact 16-16^b of relay K. The relay K, in turn, is controlled by the relay D and by the 40 relays J¹ and J², as will be described in detail hereinafter.

As shown in the drawing, section $a-b$ is unoccupied, so that track relay D is energized. The contacts of contactors H^1 , H^2 , H^3 , and H^4 are all open. The windings 11 and 12 of both relays J^1 and J^2 are de-energized and the contacts of these relays occupy their normal or right-hand positions to which they were last moved. Since normal contact 20-20^a of relay J^1 is closed, current is supplied to winding 7 of operating mechanism F^1 over a circuit which passes from trolley wire 2 through wires 21, 22 and 23, normal contact 20-20^a of relay J^1 , wires 32 and 33, winding 7 of operating mechanism F^1 and wire 29 to ground at 3. Current is also supplied to winding 7 of the operating mechanism F^2 over a branch of the circuit just traced, this branch passing from wire 32 through wire 34, winding 7 of operating mechanism F^2 , and wire 35 to ground at 3. The winding 7 of each of the operating mechanisms F is therefore energized, so that derails E^1 and E^2 are held open. Since relay D is energized, and since normal contact

39-39^a of relay J¹ and normal contact 41-41^a of relay J² are both closed, a circuit is also completed for relay K over which current flows from trolley wire 2 through wires 21 and 36, front contact 31 of relay D, wire 37, winding of relay K, wire 38, normal contact 39-39^a of relay J¹, wire 40, contact 41-41^a of relay J², and wire 42 to ground at 3. Relay K is therefore energized so that signals S¹ and S² indicate proceed. 75

In explaining the operation of the apparatus as a whole, I will first assume that with the parts in the positions just described, an eastbound car traverses track A from a point west of contactor H^1 to a point east of contactor H^4 . When the car passes contactor H^1 , the closing of contact 13-14 of this contactor completes a circuit for winding 12 of relay J^1 , and current flows from trolley wire 2 through contact 13-14 of contactor H^1 , wires 17 and 18, winding 12 of relay J^1 , and wire 19 and 19^a to ground at 3. Relay J^1 therefore opens its normal contacts and closes its reverse contacts. When normal contact 39-39 a of relay J^1 is opened, the circuit previously traced for relay K is interrupted, and relay K becomes de-energized, so that signals S^1 and S^2 indicate stop, thus prohibiting a train from entering section $a-b$ under these conditions. These signals will then continue to indicate stop until the car passes contactor H^4 .

to indicate stop until the car passes contactor H^4 for reasons which will be made clear as the description proceeds. When normal contact 20—20^a of relay J^1 is opened, the circuit for the winding 7 of each operating mechanism F is opened, and when contact 20—20^b of relay J^1 closes, current is supplied to winding 8 of operating mechanism F¹ over a circuit which passes from trolley wire 2, through wires 21, 22 and 23, reverse contact 20—20^b of relay J^1 , wire 24, normal contact 25—25^a of relay J^2 , wire 26, front contact 27 of track relay D, wires 59 and 28, winding 8 of operating mechanism F¹, and wires 57 and 29 to ground at 3. Current is also supplied to winding 8 of operating mechanism F² over a branch of the circuit just traced, this branch passing from wire 59 through wire 43, winding 8 of operating mechanism F², and wires 58 and 35 to ground at 3. The winding 8 of each of the mechanisms therefore becomes energized and operates the associated plunger 6, so that the derails E¹ and E² become closed. When derail E¹ becomes closed, it closes contact 9—9^a, and when derail E² becomes closed, it closes contact 10—10^a. Since reverse contact 30—30^b of relay J^1 is now closed, current is supplied to winding 12 of relay J^2 over a circuit which passes from trolley wire 2 through wires 21, 22 and 44, reverse contact 30—30^b of relay J^1 , wire 45, winding 12 of relay J^2 , wire 46, and thence through either wire 47 and contact 9—9^a to ground at 3, or through wire 48 and contact 10—10^a to ground 130

at 3. Relay J^2 therefore opens its normal contacts. When normal contact 25-25^a of relay J^2 is opened, the circuit for each of the windings 8 is opened, and these windings therefore become de-energized. The derails E^1 and E^2 , however, remain closed under these conditions. When normal contact 41-41^a of relay J^2 is opened, the circuit for relay K which was previously opened at normal contact 39-39^a of relay J^1 , is then also opened at normal contact 41-41^a of relay J^2 , and it will be apparent, therefore, that signals S^1 and S^2 will continue to indicate stop as long as contact 41-41^a of relay J^2 remains open even though contact 39-39^a of relay J^1 now becomes closed. As soon as derail E^1 becomes closed, the car may proceed past the derail. The parts will usually be so arranged, however, that the car will either have to stop, or else proceed at a very slow speed after it passes contactor H^1 to await the closing of the derail.

When the car passes contactor H^2 , the closing of contact 13-14 of this contactor completes a circuit for winding 11 of relay J^1 from trolley wire 2 through contact 13-14 of contactor H^2 , wires 49 and 50, winding 11 of relay J^1 , and wires 51 and 19^a to ground at 3. Relay J^1 therefore opens its reverse contacts and closes its normal contacts. When reverse contact 30-30^b of relay J^1 is opened, the circuit previously traced for winding 12 of relay J^2 is opened, and winding 12 of relay J^2 therefore becomes de-energized. Since both windings of relay J^2 are then de-energized, the normal contacts of relay J^2 remain open. When normal contact 20-20^a of relay J^1 is closed, the circuit for each of the windings 7 is then again closed, and the windings 7 become energized, thereby opening the derails E^1 and E^2 . The derail E^2 is therefore open when the car reaches this derail. The derails are so constructed, however, that a car can trail past the derails, and since the winding 7 of mechanism F^2 is energized under these conditions, the derail will be opened again immediately after the car passes the derail. When the car reaches contactor H^4 , a circuit is closed for winding 11 of relay J^2 at contact 13-14 of this contactor, and current flows from trolley wire 2, through wires 52 and 53, winding 11 of relay J^2 , and wire 54 to ground at 3. Relay J^2 therefore closes its normal contacts. When normal contact 41-41^a of relay J^2 is closed, the circuit for relay K is completed since normal contact 39-39^a of relay J^1 is then closed, and relay K becomes energized. Signals S^1 and S^2 then again indicate proceed, so that the parts are restored to the positions in which they are illustrated in the drawing.

I will next assume that a westbound car traverses track A from a point east of contactor H^4 to a point west of contactor H^1 . When the car passes contactor H^4 , the clos-

ing of contact 13-15 of this contactor completes a circuit for winding 12 of relay J^1 from trolley wire 2 through contact 13-15 of contactor H^4 , wires 60 and 18, winding 12 of relay J^1 , and wires 19 and 19^a to ground at 3. Relay J^1 therefore opens its normal contacts and closes its reverse contacts. When normal contact 39-39^a of relay J^1 is opened, relay K becomes de-energized, so that signals S^1 and S^2 indicate stop. When reverse contact 20-20^b of relay J^1 becomes closed, the winding 8 of each of the operating mechanisms F becomes energized, thus closing the derails E^1 and E^2 . The car may then proceed past derail E^2 . The parts will usually be so arranged, however, that the car will either have to stop, or else proceed at a very slow speed after it passes contactor H^4 to await the closing of the derail E^2 . When the derails E^1 and E^2 are closed, the circuit for winding 12 of relay J^2 is closed at contacts 9-9^a and 10-10^a, and relay J^2 therefore opens its normal contacts. When normal contact 25-25^a of relay J^2 is opened, the windings 8 become de-energized. When the car passes contactor H^3 , a circuit for winding 11 of relay J^1 is completed at contact 13-15 of this contactor and current flows from trolley wire 2 through contact 13-15 of contactor H^3 , wires 55 and 50, winding 11 of relay J^1 , and wires 51 and 19^a to ground at 3. Relay J^1 therefore opens its reverse contacts, and closes its normal contacts. When reverse contact 30-30^b of relay J^1 is opened, the circuit for winding 12 of relay J^2 is opened, and winding 12 of relay J^2 becomes de-energized. Both windings of relay J^2 are then de-energized, and the normal contacts of relay J^2 therefore remain open. When normal contact 20-20^a of relay J^1 is closed, each of the windings 7 becomes energized, and the derails E^1 and E^2 are opened. When the car passes contactor H^1 , a circuit is closed for winding 11 of relay J^2 at contact 13-15 of contactor H^1 , and current flows from trolley wire 2 through contact 13-15 of contactor H^1 , wires 56 and 53, winding 11 of relay J^2 , and wire 54 to ground at 3. Relay J^2 therefore closes its normal contacts. When normal contact 41-41^a of relay J^2 is closed, relay K then becomes energized so that signals S^1 and S^2 indicate proceed. The parts are then restored to the positions in which they are illustrated in the drawing.

It should be pointed out that a following car cannot close a derail after a preceding car has closed it until the preceding car has passed contactor H^4 if the preceding car is an eastbound car, or contactor H^1 , if the preceding car is a westbound car. For example, I will assume that an eastbound car has passed derail E^1 but has not passed contactor H^4 . Under these conditions the contacts of relay J^1 will occupy their normal positions, and the contacts of relay J^2 will

occupy their reverse positions. As a result, if a following eastbound car now passes contactor H^1 , winding 12 of relay J^1 will become energized, thereby closing the reverse contacts of this relay, but since normal contact 25-25^a of relay J^2 is open, the circuit for the winding 8 of each operating mechanism F is opened at this contact, and the derails E^1 and E^2 will therefore remain open. It will be apparent therefore that a following eastbound car cannot pass derail E^1 under these conditions. When the preceding car has passed contactor H^4 , however, the resultant energization of winding 11 restores the contacts of relay J^2 to their normal positions, thereby closing the circuit for the winding 8 of each of the operating mechanisms F , and thus permitting the derail to close so that the following car can then proceed in the usual manner. The operation of the apparatus if a following westbound car passes contactor H^4 , after a preceding car has closed derail E^2 but before the preceding car has passed contactor H^1 is similar to that just described and will readily be understood from an inspection of the drawing.

I will now assume that a train enters section $a-b$ of track B, and that an eastbound car approaches derail E^1 while the train occupies this section. When the train enters section $a-b$, track relay D becomes de-energized and opens its front contacts 27 and 31. The opening of front contact 31 of relay D interrupts the circuit for relay K, and relay K becomes de-energized, thus causing signals S^1 and S^2 to indicate stop, thereby warning other trains on track B not to enter section $a-b$. When the eastbound car on track A passes contactor H^1 , winding 12 of relay J^1 becomes energized, thereby opening the reverse contacts of relay J^1 and closing its normal contacts. Since front contact 27 of relay D is now open, however, the circuit for the winding 8 of each operating mechanism F is open at this contact, and the windings 8 therefore remain de-energized so that the derails E^1 and E^2 remain open. As a result, a car is prevented from passing derail E^1 as long as the train remains in section $a-b$. As soon as the train passes out of the section, however, the resultant energization of track relay D closes the circuit for the operating winding 8 of each operating mechanism F so that derails E^1 and E^2 become closed. The car may then proceed in the usual manner. The operation of the apparatus if a westbound car on track A approaches derail E^2 when section $a-b$ is occupied by a train, is similar to that just described for an eastbound car and will be readily understood from an inspection of the drawing.

One advantage of apparatus embodying my invention is that protection for cars on the electric line is obtained without the use

of signals, since the normally open derail acts as a stop requirement, and the closed position of the derail gives authority to proceed.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, an electric railway track provided with a normally open derail, a first trolley contactor adapted to be operated by a car approaching said derail, a second trolley contactor adapted to be operated by the car just after the car has passed beyond said derail, a third trolley contactor adapted to be operated by said car after said car has passed a predetermined distance beyond said second contactor, means controlled by said first contactor for at times closing said derail, means controlled by said second contactor for subsequently opening said derail, and means for preventing said derail from again becoming closed until said third contactor is operated.

2. In combination, a railway track provided with a derail having open and closed positions, a first and a second winding, means for moving said derail to its open position when said first winding is energized and for moving said derail to its closed position when said second winding is energized, means for normally energizing said first winding to move said derail to its open position, means controlled by a first trolley contactor for de-energizing said first winding and for at times energizing said second winding when a car approaches said derail to move said derail to its closed position, means controlled by a second trolley contactor for de-energizing said second winding and for energizing said first winding after said car has passed said derail to restore said derail to its open position, and means for preventing subsequent energization of said second winding to again move said derail to its closed position until a third trolley contactor is operated by said car.

3. In combination, a railway track provided with a derail having open and closed positions, first and second relays each comprising first and second windings and normal and reverse contacts arranged to become closed according as the second or the first winding is energized, means controlled by a normal contact of said first relay for moving said derail to its open position, means controlled by a reverse contact of said first relay and a normal contact of said second relay for moving said derail to its closed position,

means for energizing the first winding of said first relay when a car approaches said derail, means for energizing the second winding of said first relay when said car has passed said 5 derail, means including a reverse contact of said first relay for energizing the first winding of said second relay, and means for energizing the second winding of said second relay after said car has proceeded a predetermined distance past said derail.

and second windings and a contact member movable to a reverse or a normal position to close a reverse or a normal contact according as said first or said second windings is energized, a trolley wire associated with said electric railway track and constantly supplied with current, means for supplying the first winding of said first relay with current from said trolley wire when a car moving toward said intersection approaches said derail, means for supplying the second winding of said first relay with current from said trolley wire when said car has passed said derail, means including a reverse contact of said first relay for supplying the first winding of said second relay with current from said trolley wire when said derail is closed, means for supplying the second winding of said second relay with current from said trolley wire when said car has passed said intersection, means including a normal contact of said first relay for moving said derail to its open position, and means including a reverse contact of said first relay and a normal contact of said second relay for moving said derail to its closed position.

4. In combination, a railway track provided with a derail having open and closed positions, first and second relays each comprising first and second windings and normal and reverse contacts arranged to become closed according as the second or the first winding is energized, means controlled by a normal contact of said first relay for moving said derail to its open position, means controlled by a reverse contact of said first relay and a normal contact of said second relay for moving said derail to its closed position, a first contact arranged to be operated by a car approaching said derail, a second contact arranged to be operated by said car when said car has passed said derail, a third contact arranged to be operated by said car when said car has proceeded a predetermined distance past the point at which said second contact was operated, means controlled by said first contact for energizing the first winding of said first relay, means controlled by said second contact for energizing the second winding of said first relay, means controlled by a reverse contact of said first relay and said derail for energizing the first winding of said second relay, and means controlled by said third contact for energizing the second winding of said second relay.

7. In combination, an electric railway track intersecting a second railway track, a derail in said electric railway track adjacent said intersection having open and closed positions, a relay comprising first and second windings and reverse and normal contacts arranged to become closed according as said first or said second winding is energized, means for energizing said first winding when a car moving toward said intersection approaches said derail, means for energizing said second winding when said car has passed said derail, means controlled by a normal contact of said relay for opening said derail, means controlled by a reverse contact of said relay for closing said derail, and signals for said second track controlled in part by said relay. 100 105

40 5. In combination, first and second intersecting railway tracks, a derail in said first track adjacent said intersection having open and closed positions, means for normally moving said derail to its open position, a 45 normally open contact arranged to be closed by a car approaching said intersection in rear of said derail, means controlled by said first contact for at times moving said derail to its closed position, a second normally open 50 contact arranged to be closed by said car after said car has passed said derail, means controlled by said second contact for restoring said derail to its open position, a third normally open contact arranged to be operated 55 by said car after said car has passed said intersection, and means effective after said first contact has been operated by said car for preventing the subsequent closing of said derail until said third contact has been operated by said car.

8. In combination, an electric railway track intersecting another railway track, a derail in said electric railway track adjacent said intersection having open and closed positions, a track circuit for said other railway track including a track relay, second and third relays each comprising first and second windings and contact members movable to reverse or normal positions to close reverse or normal contacts according as the first or the second winding is energized, said contact members being arranged to remain in the positions which they were last moved after the windings which moved them there become de-energized, a home relay controlled by a front contact of said track relay and a normal contact of each of said first and second relays, a signal for said other track controlled by said home relay and arranged to indicate proceed or stop according as said home relay is energized or de-energized, a first trolley contact arranged to be operated by a car approach- 110 115 120 125 130 135 140 145 150

ing said intersection in rear of said derail, a second trolley contactor arranged to be operated by said car after said car has passed said derail, a third trolley contactor arranged to be operated by said car after said car has passed said intersection, means controlled by said first trolley contactor for energizing the first winding of said second relay, means controlled by said second trolley contactor for energizing the second winding of said second relay, means controlled by a reverse contact of said second relay and by said derail for energizing the first winding of said third relay, means controlled by said third trolley contactor for energizing the second winding of said third relay, means controlled by a normal contact of said first relay for moving said derail to its open position, and means controlled by a reverse contact of said second relay, a normal contact of said third relay, and a first contact of said track relay for moving said derail to its closed position.

9. In combination, an electric railway track intersecting a second railway track, a derail in said electric railway track adjacent said intersection having open and closed positions, a relay comprising first and second windings and reverse and normal contacts arranged to become closed according as said first or said second winding is energized, means for energizing said first winding when a car moving toward said intersection approaches said derail, means for energizing said second winding when said car has passed said derail, means controlled by a normal contact of said relay for opening said derail, and means controlled by a reverse contact of said relay for closing said derail.

In testimony whereof I affix my signature.

PAUL H. CRAGO.
